J. W. VAN METER.
PORTABLE CHLORIN DISPENSER.
APPLICATION FILED APR. 11, 1921.

1,401,293.

Patented Dec. 27, 1921.

Inventor
JAMES W VAN METER

By Bradley L. Benson
Attorney.

UNITED STATES PATENT OFFICE.

JAMES W. VAN METER, OF SAN FRANCISCO, CALIFORNIA.

PORTABLE CHLORIN-DISPENSER.

1,401,293.

Specification of Letters Patent. Patented Dec. 27, 1921.

Application filed April 11, 1921. Serial No. 460,523.

To all whom it may concern:

Be it known that I, JAMES W. VAN METER, a citizen of the United States of America, residing at 2755 Clay street, city of San Francisco, in the county of San Francisco and State of California, have invented certain new and useful Improvements in Portable Chlorin-Dispensers, of which the following is a specification.

10 The present invention is an improved portable chlorin dispenser. This application relates to the same subject matter as my application of even date, Serial No. 460,522.

15 The primary object of the invention is to provide a compact and convenient apparatus for discharging liquid chlorin from relatively small pressure cylinders, for use in fumigation, animal and insect extermination, and other operations in which liquid chlorin 20 is used.

Another object of the invention is to provide in a portable apparatus for dispensing chlorin, a convenient gage wherein the escape of chlorin may be visibly controlled and the 25 dispensing accomplished with the greatest possible accuracy.

Another object is to provide an apparatus of relatively few parts and of economical structure, which will engage typical chlorin 30 cylinders and support the same in loose ground for use in orchard or farm operations.

In this specification and the annexed drawings, the invention is illustrated in the form 35 considered to be the best, but it is to be understood that the invention is not limited to such form, because it may be embodied in other forms, and it is also to be understood that in and by the claims following the description it is desired to cover the invention in whatever form it may be embodied.

Referring to the accompanying 1 sheet of drawings;

Figure 1 is a vertical side elevation of my 45 device.

Fig. 2 is an enlarged section of the gage portion of Fig. 1.

Fig. 3 is a section on the line III—III of Fig. 1, with the chlorin cylinder removed.

50 Referring to the drawings, Fig. 1, the numeral 1 indicates a U-shaped rod which constitutes a frame for a chlorin cylinder 2, the upper transverse portion 3 forming a convenient handle. In bending the rod to 55 the U-shape shown in Fig. 1, the ends of the rod are converged slightly to form a spring

or frictional engagement with the sliding yoke members 4 and 6. The yoke member 6 is shown in Fig. 3 in plan view. It is circular in form and provided with lugs 7 and 8 60 on which are bosses 9 and 11. These bosses are bored to form a sliding fit with the ends of the rod 1.

A flange 12 is provided on the yoke 6 over which a depending flange on the base of the 65 cylinder fits snugly to secure the cylinder against accidental displacement. On that type of cylinder which is round in vertical cross section, the bottom of the cylinder is engaged by the circular opening 13 in the 70 yoke 6.

The yoke 4 is of similar construction. The central bore 13 being smaller, engages the reduced neck 14 of the container 2. The extremities of the rod 1 are threaded as shown 75 at 16 for engagement with prongs 17 adapted to be forced into the ground by the weight of the device when it is dropped forcibly, and thus support the entire structure.

I provide a swinging gage 18 which has a 80 limited rotary movement on the leg of the frame 1, which extends through apertures 19 in lugs 21, Fig. 2, and is freely slidable on the said leg and provided with a rubber washer or cushion 22 which serves to check 85 the impact of the metal parts as the device is dropped forcibly to the ground.

The gage 18 is preferably a metal casting, closed at the bottom and capped at the top by a cap 23, having a depending flange 24, 90 which is secured to the shell of the gage 18 by a set screw 26.

The inner parts of the gage 18 are of glass and in order to form a fluid tight seal and to protect the glass parts from impact 95 with metal parts, I provide a rubber buffer 27 which rests upon a disk 28 which is pressed upwardly by a threaded screw 29, extending through the base from below and secured in any desired place by a lock 100 nut 31.

A glass tube 32 rests on the buffer 27 and is plugged at the top by a rubber cork 33.

It will be seen that as the parts are assembled, the glass tube is inserted with the 105 rubber plug in place at the top. The cap 23 is applied to the gage 18 and secured by the set screw 26. By turning the screw 29 the glass tube 32 is securely held between the rubber cork 33 which abuts the cap 23 110 and the buffer 27. The rubber cork 33 has a central bore in which is forcibly fitted

an inner tube 34, which terminates in an enlarged bell portion 36, open at the bottom as indicated at 37, and graduated as indicated at 38. This portion 36 is provided 5 with a plurality of apertures 39, to permit the escape of chlorin from the tube 34 to the interior of the tube 32, which is filled with water when in use.

Chlorin is admitted from the cylinder 10 2 through a flexible conduit 41, which connects with a port 42 in the cap 23, which in turn connects with the pipe 34. By this means the chlorin enters pipe 34 and displaces water in the bell shaped portion 36, 15 the displacement being indicated by the water level which fluctuates between the graduate marks 38.

As the chlorin is under pressure, and as the pressure balances with that of the 20 water in the surrounding tube 32, the chlorin escapes in bubbles through apertures 39, and rises in bubbles as indicated at 43, and finds its way through a port 44 in the rubber cork 33, which registers with a passage 46, terminating in the nipple 47 on the cap 23. The chlorin is conducted from the nipple 47 through a flexible conduit 48 to some remote point, for fumigation, insecticide operation, or in the event that the 25 apparatus is used for gopher extermination, the conduit 48 would be placed at the entrance of a gopher hole.

The cylinder 2 is provided with the usual control valve 51, which governs the discharge 30 of the chlorin.

The shell of the gage 18 is cut away on either side as indicated at 52, in order that the gage may be visible and the discharge 35 of the chlorin watched during the operation.

The gage is also provided with a sight bore 53, in which the water level is visible, it being understood that the bores 53 and 40 52 are cut away from both sides of the shell of the gage.

Inasmuch as the gage is freely rotatable on the frame 1, and the conduits are flexible, the gage may be rotated on the frame to a position best suited to the light conditions for watching the operation.

In operation, my device is carried into the field, assembled as shown in Fig. 1. It is raised from the ground a convenient distance and allowed to drop. The weight of

the cylinder 2 forces the prongs 17 into the ground, and the entire device is rigidly supported in an upright position. The gage is filled with water to the level indicated at 54 in sight port 53 or if dry chlorin is desired I introduce in the place of water 60 in the glass tube 32 a body of fluid which is repellent to chlorin, such as kerosene. The valve 51 is opened and chlorin from the container 2 enters tube 34, displacing water therein, and discharges through ports 65 39, rising in bubbles through the water, and discharges through flexible conduit 48 to the point at which it is to be used.

I claim:

1. A portable chlorin dispensing apparatus comprising a U-shaped rod, yokes slideable on said rod and adapted to engage a chlorin cylinder at either end, ground engaging prongs secured to the ends of said rod, and a gage carried on said rod operatively connected with said cylinder whereby the discharge of chlorin from said cylinder is visible.

2. A chlorin dispensing apparatus comprising in combination with a chlorin cylinder, a frame, means carried on said frame for engaging said cylinder, a handle on said frame, a gage so mounted on said frame as to be capable of a limited swinging movement and provided with flexible pipe connection 80 with said cylinder, a tube adapted to conduct chlorin from said cylinder and discharge same below the surface of a body of water in said gage, and a delivery outlet pipe from said gage.

3. A chlorin dispensing apparatus comprising in combination with a chlorin cylinder, a frame, means carried on said frame for engaging said cylinder, a handle on said frame, a gage so mounted on said frame as 90 to be capable of a limited swinging movement and provided with flexible pipe connection with said cylinder, a tube adapted to conduct chlorin from said cylinder and discharge same below the surface of a body of 95 water in said gage and a delivery outlet pipe from said gage, the said gage being so constructed that the discharge of chlorin through the water is visible from the exterior.

In testimony whereof I affix my signature.

JAMES W. VAN METER.
